Patented May 8, 1917.

UNITED STATES PATENT OFFICE.

WILLIAM ACHTMAYER, OF MIDDLETOWN, CONNECTICUT.

ENDLESS-WEB BELT.

1,225,554.

Specification of Letters Patent.

Patented May 8, 1917.

Application filed July 10, 1916. Serial No. 108,434.

To all whom it may concern:

Be it known that I, WILLIAM ACHTMAYER, a subject of the German Emperor, and a resident of Middletown, in the county of 5 Middlesex and State of Connecticut, have invented a new and Improved Endless-Web Belt, of which the following is a full, clear, and exact description.

The invention relates to power transmission belts made of woven textile webbing, and its object is to provide a new and improved endless web belt made from a single piece of webbing joined at the ends without the use of special fastening or coupling devices 15 and arranged to present practically a uniform thickness throughout the length of the belt and without any undesirable projections on either face especially at the joint.

In order to accomplish the desired result, 20 the ends of the webbing are provided with projecting warp threads, of which the warp threads of one end are passed through an adjacent layer to extend between two layers of the body of the webbing. Use is also 25 made of longitudinally extending rows of stitches uniting the superimposed layers with each other.

A practical embodiment of the invention 30 is represented in the accompanying drawings forming a part of this specification, in which similar characters of reference indicate corresponding parts in all the views.

Figure 1 is a perspective view of the endless web belt;

Fig. 2 is a diagrammatic view of the same;

Fig. 3 is an enlarged perspective view of 35 a portion of the belt at the joint thereof and with the several layers in disassembled position;

Fig. 4 is a similar view of the same with the projecting warp threads passed between 40 adjacent layers;

Fig. 5 is a similar view of the same with 45 the layers united; and

Fig. 6 is an enlarged longitudinal section 50 of the endless web belt at the joint of the ends.

The endless web belt is made of a piece of 55 single ply webbing 10 of a woven textile material rolled up to form an endless band of two, three, four or more layers, according to the strength of the belt desired. The drawings disclose four layers but it is expressly understood that I do not limit myself to this 60 number of layers. The outer and inner ends

11 and 12 of the webbing are provided with projecting warp threads 13, 14 passed through transverse rows of apertures 15, 16 in the adjacent layers to extend lengthwise 60 between adjacent layers, that is, within the body of the belt. The successive warp threads at each end 11 and 12 are preferably of a different length, as plainly indicated in 65 Figs. 3 and 4. After the projecting ends 13 and 14 of the warp threads are in position between adjacent layers then the superimposed layers forming the body of the belt are united with each other by rows of longitudinal stitches 20, as plainly indicated in 70 Figs. 1, 5 and 6. By reference to Figs. 2, 4 and 6 it will be noticed that the projecting warp thread ends 13 and 14 extend in opposite directions and the rows of apertures 15 and 16 are located approximately opposite 75 each other so that when the layers are united the belt practically presents a uniform thickness throughout its length.

The belt is preferably treated with a saturating solution for increasing the wearing 80 qualities of the belt.

It is understood that the filling at each end of the webbing is removed to provide the projecting warp thread ends 13 and 14 for splicing purposes, as above described, 85 and these warp thread ends when pressed between adjacent layers readily flatten out and accommodate themselves. The longer warp threads have a tendency to flatten out still more at the portions projecting beyond 90 the shorter warp threads so that the thickness of the belt is not unduly increased at the joint, as will be readily understood by reference to Fig. 6.

Having thus described my invention, I 95 claim as new and desire to secure by Letters Patent:

1. As an article of manufacture, an endless web belt, comprising a flat, straight woven webbing rolled up to form an endless band of a plurality of superimposed layers, the webbing having its warp threads projecting beyond each end, the projecting warp threads of the ends of the webbing passing through the adjacent layers of the 100 webbing and extending lengthwise between adjacent superimposed layers.

2. As an article of manufacture, an endless web belt, comprising a piece of webbing formed into superimposed layers and having each end provided with projecting warp threads, certain of the layers of the 105

webbing being provided with transverse rows of holes through which extend the projecting ends of the warp threads, the said projecting warp thread ends extending 5 lengthwise between adjacent superimposed layers to join each end of the webbing to a layer thereof.

3. As an article of manufacture, a many-ply endless web belt, comprising a single 10 piece of single-ply webbing rolled up into an endless band having a body of a plurality of superimposed layers, the ends 15 of the webbing having projecting warp threads, each layer next to an end of the webbing having a transverse row of holes through which the projecting warp threads of said end extend lengthwise in a forward direction between the adjacent layers, and longitudinal rows of stitches connecting the 20 several layers of the body with each other.

4. As an article of manufacture, a many-ply endless web belt, comprising a single-

piece of single-ply webbing rolled up into an endless band having a body of a plurality of superimposed layers, the ends 25 of the webbing having projecting warp threads and the layer next to each end of the webbing having a transverse row of holes through which the projecting warp threads of said end extend lengthwise in 30 a forward direction between the two adjacent layers, the rows of holes being located approximately opposite each other, and longitudinal rows of stitches connecting the several layers of the body with each other. 35

5. As an article of manufacture, an endless web belt, comprising a piece of single-ply webbing formed into superimposed layers and having each end provided with projecting warp threads passing through the 40 adjacent layer and extending lengthwise between adjacent superimposed layers, successive warp threads being short and long.

WILLIAM ACHTMAYER.
